US00D879388S

(12) **United States Design Patent** (10) **Patent No.:** **US D879,388 S**
(45) **Date of Patent:** **** Mar. 24, 2020**

(54) **POULTRY WATER DISPENSER**

(71) Applicant: **Marc Song**, Vista, CA (US)

(72) Inventor: **Marc Song**, Vista, CA (US)

(**) Term: **15 Years**

(21) Appl. No.: **29/628,945**

(22) Filed: **Dec. 8, 2017**

(51) LOC (12) Cl. **30-03**

(52) U.S. Cl.

USPC **D30/132; D30/121**

(58) **Field of Classification Search**

(57) **CLAIM**

The ornamental design for a poultry water dispenser, as shown and described.

DESCRIPTION

FIG. 1 is a perspective view of a poultry water dispenser showing my new design;

FIG. 2 is a right side elevational view thereof, the left side elevational view being a mirror image thereof;

FIG. 3 is a front elevational view thereof;

FIG. 4 is a rear elevational view thereof;

FIG. 5 is a top view thereof; and,

FIG. 6 is a bottom view thereof.

1 Claim, 4 Drawing Sheets
